WILLIAM B. FEW, OF MONTROSE, LOUISIANA

MEANS FOR VENTILATING LATH BUNDLES

Application filed April 26, 1929. Serial No. 358,290.

This invention relates generally to ventilating means for bundles of laths or other wooden material, and more specifically to improved means adapted for incorporation 5 as a part of a bundle of laths or other wooden material which, when so incorporated, will divide the bundle into units separated from each other by spaces through which air may pass for the purpose of drying the wooden 10 material comprising the bundle.

It is well known that plaster laths and similar strips or pieces of wood are tied in bundles before being dried so that the strips or pieces of material may be handled with 15 greater facility. This situation heretofore interfered with the ready and complete drying of the strips or pieces in that the compact nature of the bundle prevented proper air or kiln drying of the material located in the 20 center of the bundle. In other words, if the bundle of material were permitted to dry a sufficient length of time to dry the material properly at the center of the bundle, the drying period was very greatly prolonged, 25 and because of this prolongation of the drying period the material at the outer surface of the bundle would dry out excessively, thus becoming brittle, a feature objectionable when used for the purpose intended.

30 In order to avoid excessively drying the material at the outer surfaces of the bundles so as to render it brittle, the bundles of material, prior to this invention, were removed from the dryer when the material at 35 the outer surfaces of the bundles was properly dried, but before the material at the center of the bundles had attained the desired dry condition, and as a result the material in the bundle was not uniformly dried. 40 In addition to the effect that the non-uniform dryness of the material had in the use of the material, the high moisture content of the incompletely dried material in the bundles resulted in the freight charges on bundles 45 of material being considerably higher than they would have been if all of the material of the bundles had been properly dried.

In view of the foregoing, I have devised 50 the means disclosed in the present application for facilitating the drying of the laths

and other wood material of a bundle of such material, said means comprising a cross-shaped member, one or more of which is incorporated as a part of the bundle. The cross-shaped members referred to serve to 55 divide each of the bundles into a plurality of portions which are separated from each other by spaces through which air may circulate, and because the separate portions of each bundle of material are each of relatively 60 limited cross-sectional dimensions when compared with the bundles as formerly constituted, all of the material may be uniformly dried during a drying period of much less duration than heretofore.

Fig. 1 is a perspective of one of my improved devices for ventilating a bundle of laths or other wooden material.

Fig. 2 is a side elevation of a bundle of laths or other wooden material having a pair 70 of my improved ventilating devices associated therewith.

Fig. 3 is a plan view of the bundle of laths or other wooden material illustrated in 75 Fig. 2.

Fig. 4 is a view showing the elements of which my improved ventilating device is comprised.

In the drawing, wherein is shown for the purpose of illustration merely one embodiment of my invention, A designates a bundle of laths and B designates a plurality of my improved ventilating devices associated with the bundle of laths. Each of the ventilating devices comprises a pair of strips of material 80 1 and 2 which are assembled in the form of a cross, as shown clearly in Fig. 1. The strips of material 1 and 2 are connected together so that the cross-like arrangement may be maintained, and the means for so connecting said strips of material may vary. However, I prefer to mortise the strips 1 and 2 together; that is to say, each of said strips at its approximate longitudinal center is provided 85 with a notch 3, which is open at one of its ends, at an edge of the strip, and said notch extends inwardly with respect to the strip from the open end thereof. Between the closed end of each notch 3 and the edge of 90 the associated strip of material opposite to 95 100

the edge thereof at which the open end of the notch is located is a solid portion 3', which is of approximately the length of the notch 3.

When the strips of material 1 and 2 are to be assembled, said strips of material are arranged at an approximate right angle to each other and with the open ends of the notches of the respective strips disposed adjacent to each other. The strips are then moved toward each other so that the solid portion 3' of each strip moves into the notch of the associated strip, and when the strips are so positioned they will be mortised together so that a unitary cross-shaped member is provided.

At the opposite ends of each of the strips of material I provide slots 4 which are open at the outer ends of the strips of material and extend inwardly thereof in a longitudinal direction. The slots 4 serve an important function which will be hereinafter referred to.

In the use of my improved ventilating devices, preferably two or more of the cross-shaped members are associated with each bundle of laths, said members being spaced longitudinally of the bundle. The bundle of laths is divided into four equal parts of approximately twelve laths each, and one bundle section of twelve laths is seated in each pair of aligned crotches or angles of the ventilators B. In view of this arrangement it is obvious that the four bundle sections will be seated in the various crotches or angles of the ventilators B, and that said bundle sections are separated from each other by spaces through which air may circulate to dry the laths of the various bundle sections.

When the laths and ventilators have been associated with each other as described, the tie wires 5 are arranged about the bundle in the usual manner, said tie wires being passed through the slots 4 at the outer ends of the strips of material 1 and 2 of which the ventilators are comprised. By passing the tie wires through the slots 4 the likelihood that the ventilators will become displaced from the bundle is eliminated.

While I describe a ventilator formed by mortising a pair of strips of material together, I do not wish to be limited to this precise arrangement, as I may connect the strips of material referred to together in various other ways. Also, while the ventilators shown in the drawing are made of wood, I reserve the right to make my ventilators of any material which may be found to be suitable.

It has been discovered in the use of my improved ventilators that the drying period in the dry kiln is reduced from approximately 192 to 96 hours, while a more uniform dryness of the laths is obtained. Also, because all of the laths are properly dried the weight of a car load of 80,000 laths is reduced approximately 2400 pounds.

I claim:

1. A ventilator for a bundle of wooden elements, comprising a cross-shaped member incorporated in a bundle of wooden elements in a manner to divide said bundle into a plurality of spaced apart sections. 70

2. A ventilator for a bundle of wooden elements, comprising a cross-shaped member incorporated in a bundle of wooden elements in a manner to divide said bundle into a plurality of spaced apart sections, said sections of the bundle being seated in crotches or angles provided by said cross-shaped member. 75

3. A ventilator for a bundle of wooden elements, comprising a cross-shaped member formed of a pair of strips of material mortised together and incorporated in a bundle of wooden elements in a manner to divide said bundle into a plurality of spaced apart sections. 80

4. A ventilator for a bundle of wooden elements, comprising a cross-shaped member incorporated in a bundle of wooden elements in a manner to divide said bundle into a plurality of spaced apart sections, said sections of the bundle being seated in crotches or angles provided by said cross-shaped member, said cross-shaped member being provided with slots adapted to receive the tying elements of the bundle. 90

In testimony that I claim the foregoing I hereunto affix my signature.
